UNITED STATES PATENT OFFICE.

WILLIAM H. LEWIS AND CHARLES A. SELEY, OF ROANOKE, VIRGINIA.

COMBINED PILOT COUPLING AND BUFFER.

SPECIFICATION forming part of Letters Patent No. 691,472, dated January 21, 1902.

Application filed March 14, 1901. Serial No. 51,111. (No model.)

To all whom it may concern:

Be it known that we, WILLIAM H. LEWIS and CHARLES A. SELEY, citizens of the United States, residing at Roanoke, in the county of 5 Roanoke and State of Virginia, have invented certain new and useful Improvements in a Combined Pilot Coupler and Buffer; and we do hereby declare the following to be a full, clear, and exact description of the invention, 10 such as will enable others skilled in the art to which it appertains to make and use the same.

Our invention relates to certain new and useful improvements in combined pilot coupler and buffer, and particularly to that class 15 known as the "Master Car-Builders" type, which are generally employed at the front end of locomotives or to other railway and rolling equipment, to which the couplers of standard length of shank cannot be applied.

20 The object of our invention is to provide a coupler of the type described which shall be economic and simple of construction and effective in operation; and with these ends in view our invention consists in the construction and arrangement of parts hereinafter 25 more specifically described, and shown in the drawings.

In order that those skilled in the art to which our invention appertains may know 30 how to make and apply our invention and fully understand all of its advantages, we will proceed to describe the construction and operation of the same, referring by letters to the accompanying drawings, in which—

35 Figure 1 represents the head of the coupler in elevation and the shank and its socket or case in central vertical longitudinal section. Fig. 2 is a transverse vertical section through the shank of the coupler, taken on the line xx of Fig. 1. Fig. 3 is a top or plan view of the 40 coupler and its case or socket in normal relation, and Fig. 4 is a front elevation of the coupler-socket.

Similar letters of reference indicate like 45 parts in the several figures of the drawings.

A represents the head of the coupler, which may be of the ordinary or any preferred construction and provided with the usual or any desired interlocking or swinging knuckles or 50 jaws.

B is the shank of the coupler, which is bored or hollowed out longitudinally to constitute a receptacle or recess for buffer-springs C D and formed with trunnions E on the upper and lower faces of the shank. The trunnions E, as clearly shown at Fig. 3, are curved on their front and rear faces for the purpose presently explained.

F and F' represent the coupler-socket made in two parts, adapted when in proper relation 60 to each other to constitute a seat and receptacle for the shank of the coupler. Each section of the socket is formed with an opening or slot G, adapted to receive the trunnions E of the coupler-shank, and the front and rear 65 walls of said sockets correspond to the curvatures of the front and rear faces of the said trunnions. The length of said sockets is such as to permit of a predetermined longitudinal movement therein of the trunnions E for the 70 purpose hereinafter explained. The two sections or halves F and F' of the socket or casting are formed with lateral lugs or ears G, provided with central orifices for the passage of bolts H, by means of which said socket- 75 sections are secured to the buffer-beam of a locomotive or to the sill of a car or tender, and with central lateral webs I, which are secured together by vertical bolts or rivets J. The socket-sections are formed with inwardly- 80 projecting shoulders or an annular flange K, adapted to constitute a stop, against which the rear end or tail of the coupler-shank may contact, and the head of the coupler is formed with shoulders or faces L, adapted to 85 contact with the forward edges or face of the coupler-socket sections F and F' whenever the resistance of the buffer-springs has been overcome in the buffing action.

M is a plate which is arranged behind the 90 shoulders or annular flange K and between the latter and the buffer-beam, and the buffer-springs C D are confined under proper compression between said plate and the base or front wall of the recess of the shank in 95 order that such compression of said springs shall operate to hold the coupler-head to its required position for coupling and pulling and to receive the cushion-buffing strains imparted to the coupler-head.

The side walls of the socket or casing diverge, as shown by dotted lines, toward the front end or are given such clearance relatively to the cross-section of the coupler-shank 5 that proper lateral movement of the shank may take place when necessary on track curvatures, the curved front and rear faces of the trunnions of the coupler-shank co-operating under such conditions.

10 In assembling the parts the springs C D are located within the bore or hollowed portion of the shank of the coupler, and the plate M is placed against the rear coils of said springs. The two sections F and F' of the socket or 15 casing are placed around the shank of the coupler, with the trunnions E located within the slots G of the casing or socket F F', and the latter are then secured together by the vertical bolts or rivets H, passing through the 20 webs I, and the parts thus assembled are secured to the buffer-beam or car-sill by the securing-bolts H in such manner as to put the springs C D under proper compression, as hereinbefore explained. When the parts are 25 thus assembled and secured in position, it will be readily understood that when a buffing strain is received at the coupler-head it will, according to its force, compress the springs C D, the slots G permitting a back- 30 ward movement of the coupler-head corresponding with the strength or resistance of the springs, and that when the resistance of the springs shall be overcome by the shock the rear faces of the trunnions will contact 35 with the rear wall of the slots G, and simultaneously the shoulders or faces L of the coupler-head contact with the front edges of the socket F F', and at the same time the tail of the coupler-shank will contact with the inwardly-projecting shoulders or flange K of the socket or casing, thus distributing the shock to several independent localities and relieving the strain upon any one locality.

When the ordinary "dead-blocks" are employed on the equipment, the coupler and buffer bears such relation thereto that the dead-blocks take up or assist in taking up the shock coincidently with the contact of the several shoulders and faces just described 45 and which could not be the case were the coupler not arranged for longitudinal or lengthwise movement, and consequently the entire buffing shocks would be transmitted through the coupler mechanism.

50 While we have shown and prefer to use the plate M as a seat for the rear ends of the buffing-springs, we do not wish to be confined to the use of the same, as said springs may be seated directly against the buffer-beam or 55 end sill, and while we have shown and described a construction which involves the taking up of the buffing shock at several localities after the resistance of the buffing-springs has been overcome we do not wish it to be 60 understood that our invention is limited to 65

such details of construction in combination with the other features of our invention as described, as many variations may be made in these and other respects without departing from the spirit of our invention, which consists in the generic idea of a combined coupler and buffer in which the shank of the coupler is provided with a recess for the reception of buffer-springs and provided with integral vertical trunnions, and a confining and supporting socket provided with openings or slots to constitute seats for the trunnions of the coupler-shank and within which said trunnions may have longitudinal and rotative movement.

Having described the construction, operation, and advantages of our combined pilot coupler and buffer, what we claim as new, and desire to secure by Letters Patent, is—

1. A pilot coupler and buffer consisting of 85 a coupler, having integral with the hollow shank thereof, vertical trunnions, a receiving and supporting socket adapted to be secured to the buffering-beam of a locomotive or end sill of a car, and formed with vertical openings or sockets to receive the trunnions of the coupler, and buffering-springs located centrally within the hollow shank and interposed between the coupler-head and buffering-beam or car-sill, substantially as and for the purpose 90 set forth.

2. The coupler having a shank recessed centrally to receive buffering-springs and provided with integral, vertical trunnions to engage with suitable slots in the socket or casing, a 100 casing adapted to be secured to the buffering-beam of a locomotive or end sill of a car, and provided with slots to receive the trunnions of the coupler-shank, and buffering-springs arranged within the recess of the coupler-shank, 105 and between the base thereof and the buffering-beam or end sill, substantially as and for the purpose set forth.

3. The combination of a longitudinally-movable coupler and shank made integral and 110 having also a laterally-vibrative movement, buffering-springs located within a central recess in the shank to resist longitudinal movements, vertical trunnions on the shank, lugs or faces on the coupler, and a socket or casing provided with vertical elongated openings to receive the trunnions of the shank, and with shoulders or projections to constitute contacts for the lugs or faces on the coupler, substantially as and for the purposes hereinbefore set forth.

4. An integral coupler and shank, the latter formed with a central longitudinal recess for buffering-springs and with vertical trunnions having curved front and rear faces, a 125 socket or casing adapted to receive the shank of the coupler and the buffering-springs and formed with vertical slots having curved front and rear terminals, substantially as and for the purposes hereinbefore set forth.

5. A coupler-head and recessed or hollow shank adapted to receive centrally-located buffing-springs, and formed with external trunnions adapted to be seated or located 5 within slots or pockets formed in a containing and supporting socket or casing, substantially as and for the purpose set forth.

In testimony whereof we affix our signatures in presence of two witnesses.
